(57) CLAIM

The ornamental design for tree grate portion, as shown and described.

DESCRIPTION

FIG. 1 is a perspective view of the tree grate portion embodying the new design;

FIG. 2 is a top plan view thereof;

FIG. 3 is a right side plan view thereof, the left side plan view being a mirror image thereof;

FIG. 4 is a front plan view thereof;

FIG. 5 is a rear plan view thereof;

FIG. 6 is a perspective view thereof, showing the remaining segments of an assembled tree grate in broken lines; and,

FIG. 7 is a top plan view thereof, showing the remaining segments of an assembled tree grate in broken lines.

FIGS. 1-7 show portions of a tree grate portion and an assembled tree grate in broken lines. The broken lines are shown for environmental purposes and form no part of the claimed design.
